UNITED STATES PATENT OFFICE.

JOHN G. H. LIEBEL AND EDWIN S. FLARSHEIM, OF CINCINNATI, OHIO.

TIME SWITCH.

Application filed October 10, 1921. Serial No. 506,612.

The invention relates to an electric switch and timing device primarily for a time indicating and time actuating manual and automatic control of the exciting current of an 5 X-ray tube, for obtaining definite exposure periods in X-ray photography.

The device provides for manual circuit closing, current interrupting and time mechanism control, after a manual time setting 10 is made, with an automatic circuit opening at the end of a measured duration, in either continuous or intermittent operations for the aggregate time. This provides for a single exposure for a definite amount or a 15 number of exposures, aggregating a definite amount, and both limited to the definite measured amount established by the time setting. The apparatus, therefore, cannot be injured by extended or over-exposure control, 20 nor accidentally affected by the operator.

An object of the invention is to provide an electric current controlling time switch with manually actuated means for starting the time mechanism and controlling the electric 25 circuit for a measured period.

Another object of the invention is to provide for an automatic and non-manual interfering control of the electric circuit after operating lapse of the switch timing mechanism for a measured duration or aggregated timing amount.

Another object of the invention is to provide a compact portable time switch for X-ray machines, one which can be held in 25 one hand of the operator, with push-button control operative by the thumb.

Another object of the invention is to provide for both a manual and an automatic circuit breaking operation, either of the said 40 operations being performed independently of the other.

An additional object is to provide for a combined action of the manual and automatic circuit breaking mechanism, wherein the circuit can be made and interrupted 45 manually and broken automatically at the end of a certain period of time.

Other objects and certain advantages will be disclosed in the description of the drawings, forming a part of this specification, and reference is made to the drawings, in 50 which:

Fig. 1 is a front elevation of the complete switch and timing device.

Fig. 2 is a central section on line 2, 2, 55 Fig. 1.

Fig. 3 is a face view of the clock-work casing, showing the relations of the tripping plate, to clock mechanism, and lever operated thereby.

Fig. 4 is a sectional view, similar to Fig. 2, showing the device in circuit closing position and illustrating a modified form of tripping plunger.

Fig. 5 is a face view of the pawl-arm and ratchet-wheel, attached to the timing mechanism outside of the clock-work casing.

Fig. 6 is a detail elevation, showing the relation of the trip-arm to the notch of the L-slot of the tripping plunger.

Fig. 7 is a detail section on line 7, 7, Fig. 2.

Fig. 8 is a plan of the spring switch.

Fig. 9 is a detail of a modified form of tripping plunger shown in Fig. 4.

Fig. 10 is a sectional view of the cam-ring.

Fig. 11 is a central sectional view, illustrating the relation of the main shaft of the timing device to the ratchet-wheel, main drive gear and clock spring for rotating said shaft.

The numeral 1 designates a hollow cylindrical insulating casing, within which the electric switch mechanism is mounted, having its top counterbored to furnish an interior circumferential shoulder 3, for seating a circular cover or cap 4, centrally bored at 5 for the reception of the upper end of a tubular bushing 6, provided adjacent its upper end with a circumferential attachment flange 7, bearing against the inside face of the cap and secured thereto by screws. The opposite end of the casing 1 is provided with a tubular extension 2, forming a hand-hold, screw threaded into the end of the casing 1.

A cylindrical plunger 10 has a sliding non-rotatable fit within the bushing 6, its lower end being normally flush with the lower end of the bushing, and its upper end extending through and above the opening 5 of the cover 4. The upper end of the plunger is bored as at 11, and screw threaded for the reception of a headed screw 12 of insulating material secured as a thumb piece for depressing the plunger and as an abutment for a compression spring 13, surrounding the plunger 10, with its lower end within the bore 5, and abutting the upper end of the bushing 6. The lower end of the plunger 10 is provided with a cylindrical bore 15 for the reception of a reciprocable and rotatable cylindrical tripping plunger 20, within the

lower end of which is a second shouldered switch contact plunger 21, the lower end of the same being provided with an insulating contact cap or base 22.

- 5 An additional form of plunger 20 is shown in Figs. 4 and 9 wherein the second shouldered switch contact plunger 21 is eliminated, the plunger 20 being of solid cylindrical construction, and being provided with 10 a reduced extension 20^a, at lower end of which is placed the insulating contact cap 22.

The plunger 21 is pressed downwardly by the action of a compression spring 23 and its 15 downward movement is limited by a ring 24, within and at the lower end of the plunger 20, the ring coacting with a shoulder 25, as an inwardly turned flange integral with the body of said plunger 20.

- 20 The plunger 20, near its upper end, is provided with an outwardly projecting trip-arm 30, at the outer end of which and depending vertically therefrom is fastened a tripping plate or knife 31, having a lower 25 knife edge 32 for contact with the outwardly extending arm 33 of a spring actuated escapement trip lever 34, pivoted as at 35 to a clock casing 36, mounted within an annular insulating housing 37, suitably fastened at 30 the side of the main casing 1, with its central axis at right angles to the central axis of the said casing 1. A pressure is exerted upon the arm 33 of the escapement lever 34 by a spring 35, the spring pressure tending to 35 force the arm 33 toward the tripping knife 31. Upon downward movement of the tripping knife, the arm 33 is engaged and depressed thereby, and the lever actuated to release the clock mechanism as hereinafter 40 more fully described.

The trip-arm 30 traverses a relatively wide slot 8, (see Fig. 6), at the bottom of the bushing 6, the upper end 8^a of the said slot acting as a stop for limiting the upward or 45 return movement of the trip-arm 30, under certain conditions hereinafter described.

- The plunger 10 is held from rotation, and its reciprocative movement limited in both directions by the end of a set screw 10^a engaged through the bushing 6, the said end of the set screw projecting into a guide slot 10^b, of the plunger 10. Placed in substantially diametrical relation to the slot 10^b and parallel to the same, is an L-slot 15^a, through 50 which the trip-arm 30 projects. The longitudinal portion of the slot being of slightly greater width than the width of the trip-arm 30, to allow said trip-arm to enter and to be guided therein after disengagement 55 from the shoulder 15^b, as herein described. A spring 15^a, attached at one end to the flange 7 of the bushing 6, slidably engages the trip-arm through an opening therein and 60 normally forces the said arm against the left side (see Fig. 6) into engagement with the

shoulder 15^b of the slot, locking the arm and its plunger against upward movement.

The trip-plunger 20 is coupled or connected to the push plunger 10 by the trip-arm 30, when the arm is engaged with the shoulder 15^b formed by the L-slot 15^a, as shown in Fig. 6. The trip-plunger with its trip-arm can be freely oscillated within the push-plunger for disengaging the arm from the shoulder 15^b, which will release the trip-plunger, allowing the arm and trip-plunger to move freely longitudinally within the push-plunger for an automatic electric circuit opening control, while the push-plunger is depressed. The release of the trip-arm and its plunger is effected by the clock or timing mechanism, to be herein-after described. The trip-plunger may be an electric switch element, or as shown, intermediate means may be employed between the push-plunger and electric spring switch for actuating and controlling the electric switch for operating as a unit with the push-plunger when connected therewith, and for operation independently thereof when disconnected therefrom. When the push-plunger is in its retracted position, the trip-arm is in registry with transversely extended portions of the L-slot, allowing the trip-arm to be oscillated by the spring 15^a which snaps the arm beneath and in engagement with the shoulder 15^b, connecting the arm and its plunger with the push-plunger, so that when the push-plunger is depressed, the parts operate as a unit for manually closing the circuit through the electric switch.

As long as the parts remain connected, they can be reciprocated as a unit for an intermittent switch control for successively interrupting the electric circuit controlled thereby until the parts have been disconnected by the timing mechanism.

The clock mechanism is mounted within the casing 36 and comprises a central main shaft 40, having the usual spiral spring 41 attached to it, and to a casing spacing, and casing fastening strut 42, the fastening and action of the spring being well known in the art of horology. The trip lever 34 (see Fig. 3) has an escapement lever engaging notch 34^a, which normally engages the out-turned end 45^a of the escapement lever 45, attached near one end of a shaft 46, and this shaft also carries the detent 47 and usual counter-weight 48. The clock escapement mechanism, comprising the escapement shaft or pivot 46, detent 47 and counter-weight 48, all well known clock elements, which when free oscillate to alternately engage and release the escapement wheel respectively to stop and permit movement thereof to obtain progressive movement of the gear train connected with the escapement wheel. The escapement lever 45 as an arm, is fixed to the escapement shaft and has its 130

end bent and projected freely through an opening in the clock casing 36, thus providing a lug or projection 45^a for engagement by the notch 34^a of the trip lever 34. The escapement lever, as a part of the clock escapement mechanism, oscillates therewith when the trip lever 34 is swung to a retracted position to disengage its notched end portion from the lug or projection 45^a of the escapement lever 45. The trip lever 34 is actuated and controlled by the knife 31 of the electric switch controlling trip plunger 20. When the knife 31 is depressed it will engage the angle extension 33 of the trip lever 34, and rock the vertically disposed arm away from the projection 45^a to allow the escapement arm to swing. As soon as the knife 31 is withdrawn from its trip lever engagement, the lever automatically swings to lug engaging position and arrests further movement of the escapement. The detent 47 engages the escapement wheel 48, mounted upon the shaft 49. The shaft 49 is provided with a pinion 50, which is operated through a gear train, composed of a gear 51, loosely mounted upon the main shaft 40, a pinion 52, and gear 53, rigidly mounted upon shaft 54, the gear 53 meshing with the pinion 50 to complete the gear train.

At the right of the clock casing 36 (see

taining and cam ring 76 is provided upon its inner circumference with a cam 77, which is engaged by the end 63^a of the pawl 63, to disengage said pawl from the teeth of the ratchet wheel 60. As the dial finger 64, approaches its zero position, the outer notched end 62^a of the pawl arm after its release, and under the action of the spring 41, engages a stop 78, formed at the end of the cam 77, as a part of the retaining and cam ring 76, stopping the finger at or beyond the zero mark, (see Fig. 1). The release of the pawl 63 from engagement with the ratchet wheel 60 takes place when the outer end of the arm 71 is spaced a certain distance from the tripping plate 31, and when the lower end of the arm 62 is spaced a certain distance from the stop 78, so that the entire propelling force of the spring is available for power shaft actuation to obtain increased speed and force of rotation or kick-off momentum, which results in positive, forcible and quick release of the trip arm 30 from engagement with the shoulder 15^b at the end of the desired timed interval between switch actuation and release.

A spacing ring 80, fitted within the bore of the housing 37 and resting against the dial plate 65, holds the said dial plate against the cam ring 76, and provides at its outer

At the right of the clock casing 36 (see Fig. 2) and adjacent its outer face is a ratchet wheel 60, mounted upon a tubular extension 61, of a gear 51, (see Fig. 11) said tubular extension being rotatively mounted upon the main shaft 40, the gear 51 and ratchet wheel 60, therefore moving independently of the shaft 40. Adjacent the outer face of the ratchet 60 is a pawl arm 62, rigidly mounted on the shaft 40, and provided at its outer end with a spring actuated pawl 63, for engagement with the teeth of the ratchet wheel 60.

On the inner end of the shaft 40 is rigidly fastened an L-shaped lever 70, the outer horizontal arm 71 of which is terminated by a knife edge projection 72, which projection normally (see Fig. 3) lies below and at one side of the tripping plate 31. To a projection of the hub of the pawl arm 62, and in a diametrical relation to said arm is fastened a dial finger 64, slightly spaced from a dial plate 65, having graduated divisions upon its face, preferably corresponding to seconds of time.

The clock casing 36 is held from rotation by a rectangular strip 36^a, fastened at the bottom of the housing 37, the notches 36^b of the clock casing plates engaging said strip. The strip extends beyond the clock casing, nearly to the outer edge of the housing 37, and the notch 75, of a retaining and cam ring 76, engages the strip 36^a, to prevent rotation of the ring, in a manner similar to that of the clock casing. The re- 60
65
125

taining and cam ring 76 is provided upon its inner circumference with a cam 77, which is engaged by the end 63^a, of the pawl 63, to disengage said pawl from the teeth of the ratchet wheel 60. As the dial finger 64, 70 approaches its zero position, the outer notched end 62^a of the pawl arm after its release, and under the action of the spring 41, engages a stop 78, formed at the end of the cam 77, as a part of the retaining and 75 cam ring 76, stopping the finger at or beyond the zero mark, (see Fig. 1). The release of the pawl 63 from engagement with the ratchet wheel 60 takes place when the outer end of the arm 71 is spaced a certain 80 distance from the tripping plate 31, and when the lower end of the arm 62 is spaced a certain distance from the stop 78, so that the entire propelling force of the spring is 85 available for power shaft actuation to obtain increased speed and force of rotation or kick-off momentum, which results in positive, forcible and quick release of the trip arm 30 from engagement with the shoulder 15^b at the end of the desired timed 90 interval between switch actuation and release.

A spacing ring 80, fitted within the bore of the housing 37 and resting against the dial plate 65, holds the said dial plate against the cam ring 76, and provides at its outer edge a seat for a transparent disk 81, placed outside of the dial finger and held in position by a flanged cap ring 82, suitably fastened to the housing 37. The shaft 40 is further provided at its outer end with a knurled nut 83, of insulating material for the purpose of setting the dial finger 64, over any of the graduations of the dial plate. 100 105

The main casing 2 is counter bored at its lower end, as at 2^a, to provide a shoulder 2^b, against which is placed a circular diaphragm 90, having a central opening 91 therein, through which projects the lower end of the plunger 21. The insulating contact cap 22 normally rests upon the upper resilient spiral arm 92, of a three-armed switch 93, having additional resilient spiral arms 94 and 95, placed below the arm 92, spaced and insulated therefrom and from each other and fastened to an insulating base 96, the terminal of each arm being fastened to the base by screws which are provided below the base 96 with nuts 97, for the attachment of line wires 98, 99, and 100, the said wires being insulated in a flexible insulat-

being suitably enclosed in a flexible insulating tube which extends through the hollow handle 2, having screw threaded engagement with the bore 2*, the base 96, resting upon a flange 102, formed at the upper end of said handle. The handle provides a means for holding the timing switch when desired, and a hook 103, is also provided for engagement over a suitable support. The operation of the timing switch is as follows: 130

Although the switch may be operated independently of the clock timing mechanism, to bring the resilient spiral arms in contact to make the electrical circuit, yet the use 5 of the clock timing mechanism is more convenient and at times more necessary for accurate timing of the breaking of the circuit as in the case of a photographic exposure, and in the latter case the nut 83 is 10 turned to set the dial finger 64 over any one of the graduations of the dial plate, with a resulting movement and displacement of the projection 72 of the L-shaped lever 70 to the left of the tripping plate 31 (see Figs. 15 5 and 6).

The plunger 10 is then depressed and with it the plunger 20 and tripping plate 31, the upward movement of the said plate 31 being prevented by the engagement of the tripping arm with the shoulder 15^a, the arm being pressed against the left side (see Fig. 20 6) of broadened portion 15^b, of the slot, by the spring 15^c. The cap 22 of the switch contact plunger 21, during the continued 25 downward movement of the plungers, successively causes contact between the spring arms 92, 94, and 95, to make an electrical circuit through the wires 98, 99, and 100. Immediately after the spring arms 92, 94 30 and 95 have made contact, the tripping plate also contacts the arm 33 of the escapement trip lever 34 and disengages its notch 34^a from the projection 45^a of the escapement lever 45, to release the detent 47, to allow 35 the clock mechanism to function. During the operation of the clock mechanism, the dial finger travels toward the zero mark of the dial plate, and the pawl arm 62, and pawl 63 in engagement with the ratchet 40 wheel 60, travel therewith. The arm 72, of the L-shaped lever 71, travels toward the tripping plate 31, and when the dial finger reaches the zero point, contacts the same, throwing the arm 30 to the right, Fig. 6, 45 and releasing the said arm from the shoulder 15^a, at which time the spring arms 92, 94 and 95 force the plungers 21 and 20 upwardly, bringing the trip arm 30 against the upper end 8^a of the slot 8, bringing the 50 tripping plate 31 above and out of the path of the projection 72 of the lever 71. When the arm 30 carrying the tripping plate 31 is released as above described, the escapement lever 34 is also released, and the arm 33 thereof raised by the action of the spring 55 35^a, and the notch 34^a disposed to prevent further movement of the escapement lever 45 by engaging the outturned end 45^a of said lever. The end 63^a, of the pawl 63, 60 then engages the cam 77 to release the said

pawl from the teeth of the ratchet wheel 60, to allow the lower end of the pawl arm to engage the stop 78 and prevent further rotation of the shaft 40 and L-shaped lever 71.

Having described our invention, we claim:

1. In an electric circuit controlling time switch, a self-opening electric circuit controlling switch, a sectional plunger, the sections cooperating unitarily for manually closing said switch and one section thereof releasable from the second for automatically opening said switch at the end of a timing period, clock mechanism for a timing switch control including a clock spring, gearing and ratchet means, the ratchet means connecting said spring and gearing, means connecting with said spring and rotated thereby adapted to engage said releasable plunger section for effecting the switch opening at the end of a timing period, and means for tripping said ratchet mechanism at the end of a timing period disconnecting the spring and clock gearing for effecting a spring release and utilizing its full recoil power for forcibly moving said plunger section for a switch opening while the second of said plunger sections is held depressed.

2. In a time control electric switch, an electric switch, manually depressible switch operating means having a member thereof releasable when depressed for automatic switch operation, a spring actuated gear train, setting means for winding said train spring and setting said train for movement through a selected time period, retaining means for holding said train in set position releasable by said switch operating means, an arm operated by said train spring for moving said switch operating member at the end of a timing period, and means for disconnecting said spring and gear train at the end of a timing period for releasing the spring whereby its full power is imparted to said arm.

3. In a device of the class described, an electric switch, manually actuated means for closing said switch, a spring actuated gear train including a member rotated by the train spring for effecting an automatic switch opening at the end of a timed period, and means connecting said spring and gear train automatically releasable, whereby the full spring pressure is transmitted to said member for a forcible automatic switch opening control.

In witness whereof, we hereunto subscribe our names.

JOHN G. H. LIEBEL
EDWIN S. FLARSHEIM.
